United States Patent Office

Des. 186,480
Patented Oct. 27, 1959

186,480

BOAT

Richard C. Cole and John A. Woodson, Miami, Fla.

Application December 3, 1957, Serial No. 48,754

Term of patent 14 years

(Cl. D71—1)

FIG. 1

FIG. 2

FIG. 3

FIG. 4

FIG. 6

We claim:

The ornamental design for a boat, substantially as shown and described.
